UNITED STATES PATENT OFFICE.

EDWARD C. BEERS, OF ROCHESTER, NEW YORK.

CONVERTIBLE COMBINATION COAL AND GAS RANGE.

1,359,864.

Specification of Letters Patent. Patented Nov. 23, 1920.

Application filed June 7, 1920. Serial No. 387,245.

To all whom it may concern:

Be it known that I, EDWARD C. BEERS, a citizen of the United States, residing at Rochester, in the county of Monroe and 5 State of New York, have invented certain new and useful Improvements in Convertible Combination Coal and Gas Ranges, of which the following is a specification.

This invention relates mainly to that class 10 of convertible coal and gas ranges having a single oven, which may be heated with solid fuel only, gaseous fuel only, or by using both fuels at the same time. In this type of range, as at present constructed, the baking oven 15 is necessarily placed adjacent to the solid fuel fire-box, and is immovable therefrom. The heating of this oven with gaseous fuels has resulted invariably in many objectionable results and faulty constructions, owing 20 to the restricted spaces for, and consequent undesirable location of the burners. In certain types of these ranges the burners are positioned in the oven and more or less cumbersome baffle plates, partitions, vent 25 flues and ducts are used to distribute the heat throughout the oven. These parts not only change the shape and reduce the size of the oven but must be heated, with consequent waste of fuel, before the oven can be brought 30 to the baking temperature. Furthermore, complicated mechanism is provided to fold or raise these burners, plates, dampers, etc., from the floor, or away from the walls of the oven, when the latter is to be heated with 35 solid fuel—where they remain to not only obstruct the oven, but again be heated with a consequent waste of fuel. If the removal of these parts by hand is required (many times when hot) the operator is discouraged and 40 at a loss to know what to do with them.

In other types of these ovens the burners and their "boxes" or partitions, are positioned in the coal flues of the range, adjacent 45 to the oven, where they obstruct the free circulation of the products of combustion when solid fuel is used, thereby causing the oven to bake slowly and unevenly—in many cases it is necessary to light the gaseous fuel burners to complete the operation of baking. 50 Burners placed in coal flues are difficult to

light, clean and replace. Many times they are not adequately supplied with air to prevent flames being smothered under certain conditions. A multiplicity of push rods, cranks and cogs, designed to open and close 55 dampers, flues and vents are also undesirable features in that they tend to confuse the operator, are liable to get out of order, and if not properly adjusted and maintained, will defeat the very purpose for which they were 60 designed.

It is obvious from the foregoing that the drawbacks in the present construction of convertible ovens, as applied to combination coal and gas ranges, are largely due to the 65 fixed position of the oven and faulty location of the gaseous fuel burners, and that these and many other defects, can be eliminated by making the wall of the oven movable (when it is desired to heat the oven with gaseous 70 fuel) to a place adjacent to the burner, the latter being positioned in a location where it cannot obstruct the solid fuel flues, or oven.

One object of my invention is the elimination of certain objectionable features and 75 faulty construction now found in the present types of convertible ovens for combination coal and gas ranges as above pointed out.

This and other objects of my invention will be fully illustrated in the drawings, described in the specification and pointed out in the claims at the end thereof.

In the accompanying drawings:

Figure 1 is a perspective view of a range embodying my invention with the front 85 thereof partially broken away to show the oven and the flues of the range in section.

Fig. 2 is a perspective view of the right hand end of the range with the end plate removed therefrom.

Fig. 3 is a longitudinal sectional view of the range, the section being taken on the line 3^x—3^x of Fig. 4.

Fig. 4 is a horizontal section of a portion of the right hand end of the range, the section being taken on the line 4^x—4^x of Fig. 3.

Fig. 5 is a longitudinal sectional view of the range similar to that shown in Fig. 3, with the walls of the oven moved adjacent 95 to the gas burner for the purpose of heating 100

the oven with gas, the section of the figure being taken on the line 5*-5* of Fig. 6.

Fig. 6 is a horizontal sectional view of a portion of the right hand end of the range, the section being taken on the line 6*-6* of Fig. 5.

Fig. 7 is a longitudinal sectional view of the range similar to that shown in Fig. 5 showing a modification of the flue for conveying the products of combustion from the gas burner through the top of the oven.

Fig. 8 is a perspective view of the movable parts of the oven.

Fig. 9 is a longitudinal sectional view of a modified form of my invention.

Fig. 10 is a longitudinal sectional view of another modified form of my invention.

In the several figures of the drawings, like reference numerals indicate like parts.

The construction of the convertible oven for combination coal and gas range is illustrated in the accompanying drawings in which reference numeral 1 indicates the frame of the range. On the left hand side of the frame is located the fire box 2 from which leads the flue 3 over the top of the oven 4 and down on the right hand side thereof to the bottom of the oven. The products of combustion from the fire in the fire box 2 pass through the flue 3 over the top of the oven 4, down on the right hand side thereof to the bottom of the oven where they are deflected by the baffle plate 5 to the front of the bottom of the oven prior to their escape into the chimney 6.

The oven 4 has a frame 7 mounted to move endwise therein. This frame comprises the left hand wall 8 and the right hand wall 9 which form the right and left walls proper of the oven. The left hand wall and the right hand wall are connected at the top and the bottom by means of the parallel cross rails 10, 10.

The oven body 4 in which the frame 7 is mounted is cut away at the right in order to permit the right hand wall 9 of the frame to move out therefrom. The right hand wall 9 has an opening 11 provided in the middle thereof in which the plate 12 is mounted to swing. This plate 12 has a flue strip 13 formed on either side thereof, which flue strips together with the plate 12 form a convertible coal and gas flue as will presently appear. The plate 12 is pivoted at the bottom of the frame 7 and extends up into the inside of the frame 7 and slightly overlaps a portion of the inside of the wall 9.

For the purpose of making the flue strips 13 extend to the outside of the wall 9, slots 14 and 15 are provided in the wall through which these flue strips project. At the top of the flue strips are provided the ears 16 which project inwardly and form stops for the purpose of limiting the movement of the

plate 12 toward the inside of the frame 7. The movement of the plate 12 against the inside of the wall 9 is limited by the contact of the plate with the inside of the portion of the wall 9 which it overlaps. In the latter case, the plate 12 closes the opening in the wall 9 while when the plate 12 is tilted back, an upwardly slanting intake flue is formed thereby. Both of these positions are shown respectively in Figs. 3 and 5.

When the oven 4 is to be heated by the products of combustion from the solid fuel burning in the fire box 2, the heated gases formed by these products of combustion pass into the flue 3 over the top of the oven, down the right hand end thereof and under the bottom from where they pass out into the chimney 6. This course taken by these gases and its heating effect on the oven 4 is the same as in most of the modern sheet flue ranges that are now in use. The gases are unobstructed in their travel through the flue 3 until they pass out into the chimney.

The space between the right hand wall 9 of the oven 4 and the outer right hand wall 17 of the range forming part of the vertical flue is divided by the partition 18. This partition has an opening 19 provided therein in which the swinging plate 20 is mounted. The opening 19 and the swinging plate 20 which forms a door therefor is located in the partition 18 at a point opposite to the opening in the right hand wall 9 and its swinging door 12.

The vertical flue 21 formed by the partition 18 and the right end plate 17 is again divided by a pair of flue strips 22, 22, which divide the vertical flue 21 into a central, vertical flue 23 and two other smaller vertical flues 24, 24, on either side thereof. In the central vertical flue 23 and adjacent to the bottom of the opening 19 in the partition 18 is mounted the gas burner 25. This gas burner 25 separates a small portion of the lower part of the central flue 23. Leading out from the lower part of this separated portion of the flue 23 is an opening 26 in front of which is provided the angular deflecting plate 27. The gas burner 25 is provided with burner holes both in the top and in the bottom so that both the top part of the central flue 23 as well as the bottom part thereof can be heated thereby, independently of each other. To provide the necessary air for the combustion of the gases from the burner 25, a door 27^A is mounted in the right end plate 17 of the range. This door opens in front of the burner 25 so that it can be easily lighted therethrough and at the same time furnishes air to both the top and bottom of the burner through suitable openings in the door.

When the range is to be converted for the purpose of heating the oven 4 by means of

the gas burner 25 either alone or together with the products of combustion from the fire box 2, the frame 7 with its left and right hand walls 8 and 9, respectively, together with the plate 12 and flue strips 13, 13, are moved to the right. In so doing the flue strips 13 of the plate 12 are moved into the opening 19 in the partition 18. When these flue strips enter the opening 19 the swinging door 20 is pushed inwardly while at the same time the plate 12 on which the flue strips 13 are formed is tilted into the interior of the oven. In Fig. 3 the oven is shown before the frame 7 is moved and in Fig. 5 the oven is shown after the movement has been completed. After the frame 7 has been moved, the plate 12 is tilted into the oven and the plate 20 is tilted into the central flue 23, the plate 20 rests on top of the flue strips 13 of the plate 12 and thus forms a convertible flue that is inclosed on all sides and leads from the top of the gas burner 25 to the inside of the oven and the frame 7. The flue thus formed is adapted to convey the products of combustion from the gas burner 25 to the inside of the oven. From the inside of the oven, the products of combustion pass out through the opening 28 near the top of the left hand wall 8. When the frame 7 has been moved to the right as previously described, a small flue 28^A is formed in back of the left hand wall 8 and the products of combustion passing through the opening 28 enter this flue and then pass out through the opening 29 in the bottom of the flue thus formed into the flue 3 under the oven, from where they pass out into the chimney 6. The products of combustion from the top of the burner 25 which pass through the oven to heat the inside thereof, also heat a portion of the bottom of the oven from the outside beginning at the point where they pass through the opening 29 and enter the flue 3.

The products of combustion which are given off from the bottom of the burner 25 pass out through the opening 26 and are deflected by the baffle plate 27 to the flue 3 under the oven in which they travel until they also pass out into the chimney 6. The products of combustion from the under-side of the burner 25 heat the whole of the bottom of the oven 4, and mix with the products of combustion from the opening 29 before they pass out through the chimney. Thus, the gas burner 25 heats the oven separately from both the inside and the outside thereof and this without interfering with the free circulation of the products of combustion from the fire box.

While the oven is being heated from the gas burner, the products of combustion from the fire box circulate without obstruction around the oven except at the right hand end thereof. At this point, instead of traveling through the vertical flue 3 at the right side

of the wall 9, before the frame 7 and wall 9 have been moved to the right, these products of combustion enter the auxiliary vertical flues, 24, 24, on either side of the central flue 23 in which the gas burner 25 is located. At the bottom of these flues 24, 24, the products of combustion pass out through the openings 31, 31, in the partition 18, and enter into the flue 3 on the under side of the oven, as do the products of combustion from the bottom of the gas burner 25.

In the event where the range contains a fire in the fire box, and it is desired to heat the oven by gaseous fuel, the products of combustion from the fire box 2 are not obstructed in their passage to the chimney 6 as they travel through the flue 3 over the top of the oven 4 and then downwardly through the auxiliary flues 24, 24, and at the point where they leave the openings 31 in the auxiliary flues 24, the products of combustion mix with the products of combustion from the underside of the gas burner 25. From this point, all of the products of combustion from the several fuels pass under the oven along the flue 3 until they meet the products of combustion from the top of the gas burner 25 below the opening 29 before they enter the exit into the chimney 6. In this way, the products of combustion from the fire box assist the products of combustion from the burner 25 in heating the oven without waste of heat from either the fire box or the burner. It will also be apparent from an inspection of Figs. 3 and 5 that, no matter what fuel is used to heat the oven, the products of combustion from the fire box as well as those from the burners heat the oven on all sides thereof.

In order to prevent the products of combustion from the top of the gas burner from entering the inside of the oven a false top 30 may be suspended a short distance below the top of the oven proper. This forms a flue in the top of the oven in which the products of combustion from the gas burner are conveyed from the outside of the right hand wall to the outside of the left hand wall of the oven without passing into the oven proper. This is shown in Fig. 7.

In Fig. 9 I have shown a modification of the oven and the gas burners for heating same. In this form, a second gas burner 32 is placed at the left hand end of the oven below the opening 29. The products of combustion from this burner pass through the opening 29 into the flue 28^A and from there through the opening 28 into the interior of the oven 4. At the same time that the products of combustion enter the oven through the opening 28 at the upper left hand corner of the oven, the products of combustion from the burner 25 enter the oven at the top of the right hand corner of the oven. The products of combustion from both of the burners

fill the oven and then pass out through the holes 33 in the bottom of the oven into the flue 3 below the oven 4. From the flue the products of combustion pass into the chimney 6.

5 The range shown in the drawings in connection with my invention is that of the well-known sheet flue type of range, but it is understood that my invention can be equally 10 as well adapted to any other type of range or any modification thereof.

In Fig. 10 I have shown still another 15 modification of the oven of the range. In this form the gas burners are located at the point where the products of combustion enter through the opening 29 into the flue 28^A and from there into the oven. The central 20 compartment in the right hand side of the oven which contained the burner 25 is used to conduct the gases from the inside of the oven to the outside of the bottom of the oven as indicated by the arrows that show 25 the path of the products of combustion from the burners when located as shown in this figure.

The movable wall 8 of the oven 4 is provided with a flange 50 which covers the opening 29 when the wall 8 is moved to the extreme left of the oven and the wall 9 is 30 provided with a circumferential flange 51 which makes the wall 9 telescope into the inside of the oven and prevents the coal gas from entering thereinto when the wall 9 is moved to the extreme right of the oven.

35 The moving of either the wall 8 or the wall 9 automatically moves the associated parts that are directly or indirectly connected thereto and operates to change the oven from the position shown in Fig. 3 to 40 that shown in Fig. 5, or vice versa.

I claim:

45 1. In a convertible combination coal and gas range, the combination of an oven, a fire box for burning solid fuel, a flue leading from said fire box around said oven, a gas burner outside of said flue and separated from said oven by said flue, means projecting through said flue to connect said gas burner with said oven to convey the 50 products of combustion from said burner to said oven.

55 2. In a convertible coal and gas range, the combination of an oven, a movable wall on one side of said oven, a gas burner outside of said oven, said movable wall being adapted to be moved toward said gas burner, a movable flue mounted in an opening in said movable wall and forming a door therefor, said flue being adapted to convey the 60 products of combustion from said gas burner to said oven.

65 3. In a convertible combination gas and coal range, the combination of an oven, a flue surrounding said oven, a gas burner mounted outside of said flue and separated

therefrom, a movable wall in said oven, said movable oven wall being adapted to be moved toward said burner, means in said movable wall to convey the products of combustion through said movable wall into 70 said oven, a vertical auxiliary flue on one side of said burner to conduct the gases passing through said flue.

4. In a convertible combination gas and coal range, the combination of an oven, a 75 flue passing over the top side and bottom of said oven, a compartment on the outside of said flue, an auxiliary flue adjacent to said compartment on one side thereof, a gas burner mounted in said compartment, means 80 to conduct the products of combustion from said burners in said compartment to said oven.

5. In a convertible combination gas and coal range, the combination of an oven, a 85 flue surrounding said oven, a portion of said oven being adapted to move and project into said flue, an auxiliary flue outside of said flue to conduct the gases around the portion of the flue that is obstructed by 90 said movable oven portion.

6. In a convertible combination gas and coal range, the combination of an oven, a flue passing over the top, side and bottom of said oven, a compartment outside of said 95 flue and parallel therewith, a burner forming a partition in said compartment, said burner being adapted to independently supply heat for either side of said compartment, the products of combustion from one 100 part of said compartment being conducted into the oven and the products of combustion from the other part of said compartment being conducted along the outside of the bottom of said oven. 105

7. In a convertible combination gas and coal range, the combination of an oven having a flue passing over the top, side and bottom thereof, a gas burner outside of said flue and means to conduct the products of 110 combustion from said gas burner parallel to said flue, partially on the inside of said oven and partially on the outside of said oven.

8. In a combination gas and coal range, 115 the combination of an oven, a coal flue passing over the top, side and bottom of said oven, a gas burner, a pair of walls mounted to move inside of said oven to form a gas flue on either side thereof, one of said gas 120 flues being adapted to convey the products of combustion to said oven and the other of said flues being adapted to conduct the products of combustion from said oven.

9. In a convertible combination gas and 125 coal range, the combination of an oven, a flue passing over the top, side and bottom of said oven, a compartment on the outside of said flue, an auxiliary flue adjacent to said compartment on one side thereof, a gas 130

burner mounted in said compartment, means to conduct the products of combustion from said burner in said compartment to said oven, a second gas burner, means to conduct 5 the products of combustion from said second gas burner into said oven at a point opposite to the entrance of the products of

combustion from said first named gas burner, and means to simultaneously exit all of the products of combustion from both 10 of said gas burners from said oven.

In testimony whereof I affix my signature.

EDWARD C. BEERS.
